UNITED STATES PATENT OFFICE

1,958,805

REFRIGERATING SYSTEM

Charles L. Sieloff, Wellston, Mo., assignor to
Sieloff Packing Company, St. Louis, Mo., a
corporation of Missouri

Application February 16, 1933, Serial No. 656,982

6 Claims. (Cl. 261—116)

This invention relates to improvements in refrigerating systems, and consists of the novel construction hereinafter disclosed.

An object of the invention is to provide a refrigerating system comprising a portable unit adapted to be installed in a closed cooling chamber for causing a circulation and cooling of the air within the chamber by passing currents of air through the unit in contact with cooled brine 5 sprays, accumulating the brine and discharging it from the unit, and then forcing the air through air ducts equipped with means for freeing the air from moisture into the cooling chamber.

The specific advantages of the invention will 15 be apparent from the detailed description thereof, taken in connection with the accompanying drawing, in which—

Fig. 1 is a front elevation with parts broken away to more fully disclose the construction.

Fig. 2 is a vertical section taken substantially 20 on the line 2—2 of Fig. 2.

In the embodiment of the invention illustrated in the drawing, the refrigerating unit is shown as comprising a portable base 1 provided with 25 legs or standards 2. Upon the base 1 is mounted a longitudinal box 3 constituting an accumulating chamber for the cooling liquid, which liquid may be withdrawn from the box through a discharge pipe 4. A longitudinal baffle wall 5 is 30 supported by the inner face of the top wall of the box 3 and extends downwardly in an inclined direction, as clearly illustrated in Fig. 2. The box 3 is provided with an additional baffle wall 6 that extends upwardly from a lower corner of 35 the box, also as clearly illustrated in Fig. 2. The purpose of the baffle walls will be apparent from a description of the operation of the device which follows at a later point in this specification.

Connected into the top wall of the box 3 and 40 supported thereby is a longitudinal series of cylindrical pipes 7 forming chambers 8. The pipes 7 enter through openings in the top wall of the box 3 and extend upwardly therefrom to a point spaced from the ceiling 9 of the cooling chamber, 45 it being understood that the ceiling 9 of the cooling chamber constitutes a top wall for the unit. If desired, an additional wall may be substituted for the ceiling and formed as a part of the unit.

A transverse spray header 10 extends across 50 the upper ends of the series of pipes 7 and has connected thereto a series of nozzles 11, a nozzle being axially arranged in respect of the upper end of each of the pipes 7, the discharge ends 55 of the nozzles extending into the upper ends of said pipes.

Along the opposite side of the top of the box 3 is a series of pipes 12, the lower ends of which are mounted in openings in the top wall of the box 3 and are supported thereby. At the upper end of each of said pipes 12 is an elbow 13 directed outwardly from the unit and into the cooling chamber. The pipes 12 are fitted with a series of horizontally arranged screens 14, the screens 14 being spaced at selected intervals throughout the length of the pipes 12.

It will be understood that the spray header 10 is supplied with cooled brine liquid under pressure through a supply pipe 15 controlled by a valve 16. The supply of the brine liquid may be from any suitable cooling apparatus such, for example, as a brine tank provided with expansion coils, it being understood that the brine liquid is advanced by a pump under pressure and that it is cooled so that the discharge temperature from the nozzles will be approximately in 75 a range from 15° to 20° Fahrenheit.

By reference to the drawing, it will be noted also that a longitudinal baffle wall 17 is positioned between the rows of pipes 7 and 12. The baffle extends from the top face of the box 3 to the upper wall 9 of the unit to prevent the cross-draft of currents of air across the upper end of the unit and to force the currents of air entering the unit into the pipes 7.

From the foregoing description, it will be 85 understood that the operation of the device is as follows: The brine liquid under pressure is admitted to the spray header from the supply pipe 15 and is discharged under pressure from the nozzles 11, thereby forcing a spray downwardly in each of the pipes 7. Inasmuch as the spray nozzles are set within the upper ends of the pipes, a suction will be created, drawing a volume of air inwardly in the upper ends of said pipes, which air is commingled with the cooling 90 spray and driven downwardly through the pipes and into the box 3. The liquid from the sprays is deflected by the baffle 5 and accumulates in the bottom of the box 3. Any splash caused by the falling spray is prevented from entering the 100 bottoms of the pipes 12 by the baffle 6. A gravity separation of the liquid from the air occurs in the box 3 and the air, substantially freed from moisture, is forced into the pipes 12 and driven outwardly into the cooling chamber. The upward passage of the air currents through the pipes 12 and through the screens 14 tends to drop out any entrained liquid in the outwardly moving currents of air, so that the air forced from the outlet of the pipes 12 is substantially dry.

The forced movement of the air currents outwardly from the pipes 12 causes currents of air to be set up in the cooling chamber, which circulate generally from the upper part of the 5 cooling chamber downwardly toward the floor thereof, thus coming into contact with objects such as meat carcasses suspended in the cooling chamber.

I am aware that the invention may be modified in numerous particulars without departing 10 from the spirit and scope thereof. I do not limit myself, therefore, to the exact construction shown and described, but what I claim and desire to secure by Letters Patent is:—

15. 1. In a refrigerating system, the combination of a portable base, a longitudinally rectangular box supported by said base constituting a liquid accumulating chamber, a longitudinal series of pipes supported by the top wall of said box and 20 extending thereinto, a spray nozzle located in the upper end of each of said pipes, a second series of pipes arranged in a longitudinal series parallel with said first named pipes and supported by the top wall of said box and extending 25 thereinto, a baffle in said base below and preventing spray from entering said second series of pipes, and a longitudinal baffle wall located between said two series of pipes.

2. A refrigerating system comprising a rectangular hollow chamber, a series of pipes supported 30 by and having an outlet opening below the top wall of said chamber, a second series of pipes supported by and having an inlet opening below the top wall of said chamber, a baffle wall in said chamber between and extending downwardly beyond the lower ends of said series of pipes, a spray header positioned across the upper ends of said first series of pipes, nozzles carried by said spray header and extending respectively into the open 35 upper ends of said first series of pipes, and means for supplying cooling liquid to said spray header.

3. A refrigerating system comprising a rectangular hollow chamber, a series of pipes supported 40 by and having an outlet opening below the top wall of said chamber, a second series of pipes supported by and having an inlet opening below the top wall of said chamber, a baffle wall between the lower ends of said series of pipes, a baffle wall arranged within said chamber and extending 45 downwardly from the top wall thereof, the lower end of said baffle wall terminating in an area below the outlet ends of said first series of pipes, a spray header positioned across the upper ends of said first series of pipes, nozzles carried by said spray header and extending respectively into the open upper ends of said first series of pipes, and means for supplying cooling liquid to said spray header.

4. A refrigerating system comprising a rectangular hollow chamber, a series of pipes supported by and having an outlet opening below the top wall of said chamber, a second series of pipes supported by and having an inlet opening below the top wall of said chamber, a baffle wall between the lower ends of said series of pipes, a baffle wall arranged within said chamber and extending downwardly from the top wall thereof, the lower end of said baffle wall terminating in an area below the outlet ends of said first series of pipes, a second baffle wall within said chamber extending upwardly and inwardly from the bottom thereof and terminating below the area of the inlet ends of said second series of pipes, a spray header positioned across the upper ends of said first series of pipes, nozzles carried by said spray header and extending respectively into the open upper ends of said first series of pipes, and means for supplying cooling liquid to said spray header.

5. A refrigerating system comprising a rectangular hollow chamber, a series of pipes supported by and having an outlet opening below the top wall of said chamber, a second series of pipes supported by and having an inlet opening below the top wall of said chamber, a series of reticulated screens located in each of said second named series of pipes, a baffle wall between the lower ends of said series of pipes preventing spray from entering said second series of pipes, a spray header positioned across the upper ends of said first series of pipes, nozzles carried by said spray header and extending respectively into the open upper ends of said first series of pipes, and means for supplying cooling liquid to said spray header.

6. A refrigerating system comprising a rectangular hollow chamber, a series of pipes supported by and having an outlet opening below the top wall of said chamber, a second series of pipes supported by and having an inlet opening below the top wall of said chamber, a series of reticulated screens located in each of said second named series of pipes, an inclined baffle in said chamber for deflecting the liquid from the outlet ends of said second named series of pipes, a baffle wall below the lower ends of said second series of pipes preventing spray from entering said second series of pipes, a spray header positioned across the upper ends of said first series of pipes, nozzles carried by said spray header and extending respectively into the open upper ends of said first series of pipes, and means for supplying cooling liquid to said spray header.
